United States Patent

Des. 241,993
Patented Oct. 26, 1976

241,993

COUCH

Robert J. Marks, 210 Johnson Ferry Road,
Atlanta, Ga. 30328

Filed Mar. 4, 1975, Ser. No. 555,258

Term of patent 14 years

Int. Cl. D6—01

U.S. CL. D6—63

Fig 1

Fig 3

Fig 2

Fig 4

Fig 5

FIG. 1 is a perspective view of a couch embodying my new design;

FIG. 2 is a front elevational view of the couch shown in FIG. 1;

FIG. 3 is a side elevational view of the couch shown in FIG. 1;

FIG. 4 is a top elevational view of the couch shown in FIG. 1; and

FIG. 5 is a bottom view of the couch shown in FIG. 1. That side of the couch not shown is a mirror image of that side shown.

I claim:

The ornamental design for a couch, substantially as shown and described.
